(57) **CLAIM**

The ornamental design for a charging base for game controller, as shown and described.

DESCRIPTION

FIG. 1 is a perspective view of a charging base for game controller showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the encircled portion "9" in FIG. 1;

FIG. 10 is an enlarged view of the encircled portion "10" in FIG. 1;

FIG. 11 is an enlarged view of the encircled portion "11" in FIG. 2; and,

FIG. 12 is an enlarged view of the encircled portion "12" in FIG. 2.

The equal-length broken lines depict portions of the charging base for game controller that form no part of the claimed design.

The dash-dot lines in FIG. 1, 2, 9, 10, 11 and FIG. 12 illustrate the boundaries of the enlarged view indicators and form no part of the claimed design.
